UNITED STATES PATENT OFFICE

151,573

DESIGN FOR A FUR COAT

Joseph Weckstein, New York, N. Y.

Application June 11, 1947, Serial No. 139,586

Term of patent 14 years

(Cl. D3—4)

To all whom it may concern:

Be it known that I, Joseph Weckstein, a citizen of the United States, residing at New York city, in the county and State of New York, have invented a new, original, and ornamental Design for a Fur Coat, of which the following is a specification; reference being had to the accompanying drawing, forming a part thereof.

Fig. 1 is a perspective view of a fur coat, showing my new design.

Fig. 2 is a rear elevational view of the fur coat shown in Fig. 1 in spread condition.

Fig. 3 is a fragmentary developed view of the fur coat shown in Fig. 1 laid out flat.

The front of the fur coat is conventional.

I claim:

The ornamental design for a fur coat, substantially as shown and described.

JOSEPH WECKSTEIN.
